UNITED STATES PATENT OFFICE.

MARIUS HENNINGS, OF SAN FRANCISCO, CALIFORNIA.

INCINERATING-FURNACE.

1,318,666.

Specification of Letters Patent.

Patented Oct. 14, 1919.

Application filed May 29, 1918. Serial No. 237,307.

To all whom it may concern:

Be it known that I, MARIUS HENNINGS, a citizen of the United States, and a resident of the city and county of San Francisco and State of California, have invented a new and useful Incinerating-Furnace, of which the following is a specification.

My invention relates to incinerators, and one of the objects of the invention is to provide an incinerator for the efficient reduction of garbage and other waste.

Another object of the invention is to provide improved means for passing the gaseous products of evaporation and combustion through flames from the fire chamber.

The invention possesses other features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claim.

Referring to the drawings:

Figure 1 is a sectional view taken in the vertical plane passing through the center of the furnace longitudinally.

Fig. 2 is a sectional view taken in the vertical plane indicated by the line 2—2 of Fig. 1.

Fig. 3 is a sectional view taken in the vertical plane indicated by the line 3—3 of Fig. 1.

Fig. 4 is a sectional view taken in the horizontal plane indicated by the line 4—4 of Fig. 1.

Fig. 5 is a sectional view taken in the horizontal plane indicated by the line 5—5 of Fig. 1.

The incinerating furnace of my invention is preferably built with brick walls suitably reinforced with iron members 2, and lined with fire brick. A heavy layer 3 of corrugated asbestos, or of magnesia is incorporated in the walls of the furnace to aid in retaining the heat therein. A receiving or drying chamber 4 is arranged in the front upper portion of the furnace, into which garbage may be introduced through two charging ports 6 and 7, normally closed by the doors 6' and 7' respectively. Preferably wet garbage is introduced through the

port 7 in the roof of the furnace, and dry garbage through the port 6 in the front wall. The bottom or floor of the drying chamber is formed by spaced grate bars 8 overlying the fire chamber 9, and lying adjacent the dry garbage charging port 6, and by the relatively thin inclined wall 11 overlying the flue 12. The wall 11 forms a drying platform for the reception of wet garbage introduced through the port 7.

The fire chamber 9 is provided with a port 13 for the introduction of fuel. Grate bars 14 overlying the ash pit 16 form the bottom of the fire chamber. The flue 12 underlying the sloping wall 11 connects the fire chamber with the combustion and cinder collecting chamber 17 at the bottom of which an opening normally closed by the door 18 provides a means for removing matter accumulated therein. At the bottom, the combustion chamber is connected by the passage 19 with the base of the stack through which the products of combustion from the furnace pass into the atmosphere.

The dry or relatively dry garbage upon the drying grate 8 is quickly dried out and ignited by the flames from the fire chamber 9. The hot smoke and gases from this source, and the hot wall 11, heated from the flue 12, effect the drying of the wet garbage, which gradually works down from the sloping wall 11 onto the drying grate 8 where it is ultimately consumed, the residue falling through the grates and collecting in the ash pit.

Means are provided for passing the gases and vapor arising from the drying material through the flames from the fire chamber. In the vertical side walls of the furnace, channels 21 are disposed. Preferably the channels extend from the top of the drying chamber 4 downwardly past the drying grate 8 and platform 11 and are continued in the sides of the fire chamber 9 and flue 12. When the garbage is introduced into the drying chamber it extends into these channels perhaps for a short distance, but the channels are not filled completely and each one still functions as a passage through which the gases and vapor from the drying material are drawn downwardly from the drying chamber into the fire chamber and flue, where mingling with the flames therein, the remaining inflammable matter is reduced and all odors destroyed. The remaining unconsumed gases pass up the stack

into the air. Preferably a recess 23 is cut in the sloping wall 11 opposite each channel so that the opening through the wall is enlarged.

5 I claim:

In an incinerator, a drying chamber having a floor formed of a drying grate and a sloping wall, a charging port in the top wall of said chamber over said sloping wall, 10 a second charging port in the end wall of said chamber adjacent said drying grate, a fire chamber below said drying grate, a combustion chamber, and a flue connecting said fire chamber and said combustion chamber

and underlying said sloping floor, the side 15 wall of said drying chamber being formed with a plurality of channels connecting said drying chamber with said fire chamber and flue, said channels extending past the floor of the drying chamber and being continued 20 in the side walls of said fire chamber and of said flue.

In testimony whereof I have hereunto set my hand at San Francisco, California, this 4th day of May, 1918.

MARIUS HENNINGS.

In presence of—

H. G. PROST.
